Fig - 6

FIG. 1 is a plan view of a cushioned bath aid, showing my design;

FIG. 2 is a side elevational view thereof;

FIG. 3 is a front elevational view thereof;

FIG. 4 is a rear elevational view thereof;

FIG. 5 is a bottom plan view thereof; and

FIG. 6 is a cross-sectional view taken in the plane indicated by the line 6—6 in FIG. 1.

I claim:

The ornamental design for a cushioned bath aid, as shown.
